UNITED STATES PATENT OFFICE.

THOMAS N. HENCHY AND EDWARD P. FEICKER, OF NORTHAMPTON, MASS.,
ASSIGNORS OF ONE-HALF TO E. E. WOOD, OF SAME PLACE.

PROCESS OF FORMING ORNAMENTAL DESIGNS ON METAL.

SPECIFICATION forming part of Letters Patent No. 268,486, dated December 5, 1882.

Application filed June 9, 1882. (No specimens.)

To all whom it may concern:

Be it known that we, THOMAS N. HENCHY and EDWARD P. FEICKER, citizens of the United States, residing at Northampton, in the county of Hampshire and State of Massachusetts, have invented new and useful Improvements in Processes for Forming Ornamental and other Figures on Metal, of which the following is a specification.

10 This invention relates to improvements in processes for ornamenting metals by the application of acids thereto upon exposed portions of the surface constituting figures or characters, technically termed "biting in," the object being to greatly simplify the art of so producing characters and figures upon metal, and to provide improved means for reproducing or duplicating said figures to any extent at very small expense.

20 In producing characters and ornamental figures upon metal heretofore by the biting-in process it has been customary to cover a polished metal plate with a composition technically called "ground," consisting of a varnish-like substance, and then trace the design thereon by a pointed tool, which lays bare the metal wherever it goes, after which the acid is applied, which corrodes the metal on the lines made through the ground, and finally said

25 ground is washed off, leaving the distinct corroded lines; or, said characters have been produced on the metal by transferring them, by means of a thin paper, from an engraved and inked plate, to said metal, then covering said

30 ink-characters and the metal surrounding them with a thin varnish ground impermeable to turpentine, excepting upon the inked lines, next washing out the said ink-lines with benzine or turpentine, and then applying acid upon the

35 metal exposed by said lines, and finally washing off the ground and acid after the latter has sufficiently corroded the metal to cause the said characters to appear distinctly upon the metal.

40 It will be seen that the above-described processes involve many operations and the employment of skilled operatives.

To carry our invention into effect, we cover the metal with a thin ground of guiac-varnish,

and having prepared a soft or elastic-faced stamp, of rubber, cork, or leather, bearing upon its face the design or characters to be reproduced on the metal, we moisten the face of said stamp with a paste of some suitable fixed alkali—such as potash or soda—and pressing said stamp upon said ground, the portions of the latter corresponding to the figures upon said stamp are at once removed by the action of said alkali. Acid is now applied to the metal from which the alkali removed the ground, and is left to sufficiently corrode, when the acid and ground are washed off, leaving a clearly-defined figure on the metal, corresponding to that on said stamp; or, in a few words, we apply to the metal a ground of suitable material to resist the action of the metal-corroding acid, and with an elastic-faced stamp having the desired characters formed upon its face, to which is applied a ground-removing substance, we imprint the desired figures through said ground to permit the acid to act upon the surface of the metal from which the ground is so removed, and produce the counter-part of the figure on said stamp.

This process is especially advantageous for ornamenting swords, various articles of wearing-apparel ornaments, for fixing manufacturers' names and marks upon all kinds of cutlery, and for any purpose wherein metal of which an article is made is susceptible of corrosion by acid, and may be used in ornamenting glass.

We do not limit ourselves to the use of guiac-varnish (gum-guiaac mixed with alcohol) as a ground, nor to the use of an alkali as a ground-removing element to be used with the ornamenting-stamp, since a common varnish consisting of drying oil, turpentine, and African copal may be used for the ground, and benzine be used on the stamp for removing said ground to form the figure-lines, but not with so good results as by the use of guiac-varnish and an alkali.

What we claim as our invention, is—

1. The process of producing "bitten-in" figures and characters upon metals, which consists in applying a ground to the surface thereof, consisting of gum-guiaac varnish, and then cutting figure forms through said ground to

expose the metal beneath by applying thereto an elastic-faced figure-bearing stamp having applied thereto a ground-removing element consisting of an alkali, then applying acid to 5 said figure forms, and finally washing off said acid and ground, all substantially as set forth.

2. The improvement in processes for ornamenting metals by the application of acid thereto through figure forms in a ground of gum- 10 guiac varnish applied to the metal, which con-

sists in producing said figure forms by applying a figure-stamp to said ground, having upon its face an alkaline ground-removing element, all substantially as described.

THOMAS N. HENCHY.
EDWD. P. FEICKER.
